UNITED STATES PATENT OFFICE.

AUGUST J. KREUZKAMP, OF CHICAGO, ILLINOIS, ASSIGNOR TO ENGLANDER SPRING BED COMPANY, OF BROOKLYN, NEW YORK, A CORPORATION OF NEW YORK.

DESIGN FOR A WICKER END BED.

Application filed June 28, 1922. Serial No. 2,850. Term of patent 7 years.

To all whom it may concern:

Be it known that I, AUGUST J. KREUZKAMP, a citizen of the United States, residing in Chicago, county of Cook, and State of Illinois, have invented a new, original, and ornamental Design for Wicker End Beds, of which the following is a specification, reference being had to the accompanying drawing, forming a part thereof.

The drawing is a perspective view illustrating my new design.

I claim as my invention:

The ornamental design for a wicker end bed, substantially as shown.

Signed at Chicago, county of Cook, State of Illinois, this 23 day of June, 1922.

AUGUST J. KREUZKAMP.
